UNITED STATES PATENT OFFICE.

GUSTAV F. STORM, OF SANBORN, IOWA.

VALVE LIFTER AND COMPRESSOR.

Application filed February 18, 1926. Serial No. 89,089.

My invention relates to a combined valve lifter and compressor, and it is my object to provide a valve lifter of simple tongs type which is of simple, durable, and inexpensive construction, and which can be quickly changed to serve either as a lifter or a compressor.

Another object of my invention is to provide a combined lifter and compressor in which the change from lifting to compressing form is made by simply reversing one of the members of a pair of tongs which is pivoted to a fulcrum secured to the other member, the fulcrum being designed to receive the pivoted member in any of several adjusted positions, whereby the normal distance between the jaws can be varied.

Another object of my invention is to provide means for locking the handles of the tongs against movement either toward or from each other, said means being such that the changing of the device from a lifter to a compressor is not interfered with.

A still further object is to provide such a locking means which is normally automatically urged away from locking position, but which is retained in locking position by tension or pressure between the handles of the device.

More particularly, it is my object to provide such a locking means comprising a rack-bar pivoted to one of the handles, adapted to coact with a pin secured to the other handle, the rack-bar being normally spring-urged away from said pin, but so constructed as to be retained against such receding movement by engagement of the pin in the notches of the rack-bar under the influence of either tension or pressure between the handles.

With these and other objects in view, my invention consists in the construction, arrangement, and combination of the various parts of my device, whereby the objects contemplated are attained, as hereinafter more fully set forth, pointed out in my claims, and illustrated in the accompanying drawings, in which:

Fig. 1 is a perspective view of my invention,

Fig. 2 is a longitudinal sectional view of the device in position to be used as a lifter, Fig. 3 is a similar view illustrating the device in position to be used as a compressor, and

55

Fig. 4 is an enlarged detail view of a portion of the rack-bar.

The advantage of combining a valve lifter and compressor lies in the fact that under some conditions it may be more desirable to lift a spring, whereas under others it may be preferable to compress it. To combine the lifter and compressor in one tool is obviously an advantage in that the expense of obtaining both a lifter and a compressor is decreased, and the mechanic will find it easier to keep track of a single tool than two.

In the valve lifter art it has been recognized that the ordinary tongs type of valve lifter is the most satisfactory. My invention therefore aims to provide a combined compressor and lifter of the tongs form, and in so doing the main problem encountered is that of providing means for locking the handles together, and to so construct said locking means that it will serve in locking the handles against movement in either direction accordingly as the device is used as a compressor or lifter, and yet to obtain a simple arrangement by which the locking means can be spring-urged in one direction, and operable in the other direction by the finger of the operator with relation to locking position.

I have obtained this result in a simple manner in a device embodying a pair of tong members A and B, each of which comprises a handle having a channeled portion 10, a rolled handle proper 11, and a jaw member 12. The jaw members 12 are formed by spreading the sides of the channel member 10 to form the side flanges 13, flattening out the intermediate portion to form the lifting shoulder 14, and providing 95 the slot 15 therein.

The handle members may be formed in the ordinary manner from sheet-metal stampings.

A fulcrum 16 is secured between the sides 100

of the channeled portion 10 of the member B by means of rivets 17. A number of openings 18 are provided in the fulcrum 16, and are spaced longitudinally thereof in order to allow adjustment of the tong member A to and from the member B.

The member A is provided with openings 19, designed to register with any one of the openings 18, and to receive a pintle 20 for pivoting the members together. A slot 21 is provided in the web of the channel 10 of the member A, to receive the fulcrum 16, and it is of such width as to allow pivoting movement of the member A relative to the 15 fulcrum.

In Figs. 1 and 2 the members A and B are shown adjusted to act as a spring lifter, the jaws 12 opening in the same direction. In Fig. 3 the member A has been 20 simply removed by removing the pin 20, then reversed and replaced over the fulcrum in such reversed position. The device thereby is adapted to act as a compressor, the jaws 12 opening toward each other.

25 The locking device comprises a rack-bar 22, pivoted at 23 to the member B. A spring 24 secured in the rack-bar and in the fulcrum 16 under compression tends to urge the rack-bar 22 away from the fulcrum 16. 30 A foot 25 formed on the rack-bar 22 is adapted to engage the web of the channel 10 to limit the motion of the rack-bar in this direction, approximately as indicated in dotted lines in Fig. 3.

35 A slot 26 is formed in the web of the channel 10 of the member A to receive the rack-bar 22. A pin 27 is secured between the sides of the channel 10 of the member A, in such position as to be receivable in 40 any of the notches 28 which are formed in the side of the rack-bar facing the fulcrum 16. The pin is so positioned relative to the slot as to allow the rack-bar to recede a sufficient amount before contacting with the 45 edge of the slot, to clear the pin of the rack-bar.

It will now be seen that the spring 24 will normally maintain the rack-bar away from engagement with the pin 27. When a 50 spring is being engaged by the lifter, however, it is desirable and almost necessary that the rack bar be adapted to lock itself in engagement with the pin so that the hands of the operator may be removed. To this end I form the notches 28 expanded inwardly away from the edge of the rack-bar, as shown in Fig. 4. The notches are expanded in either direction longitudinally of the bar, and thus there is provided for each notch a 55 pair of inclined shoulders 29 restricting the notches at the edge of the bar.

I find the shoulders can be best formed by providing the notches 28 of substantially circular form and connected with the edge of

the bar by restricted neck openings 30 just wide enough to allow passage of the pin 27.

It will now be seen that spring pressure against the tongs, tending to urge the handles either apart or together, will cause the pin 27 to engage one or the other of the shoulders 29 in such a manner and with sufficient grip to prevent receding movement of the rack-bar 22 under the urge of the spring 24.

When it is desired to release the locking 75 device the handles are simply compressed or expanded against the action of the valve spring, and the rack bar 22 will, under the urge of the spring 24, recede from the pin 27 until the neck opening 30 registers 80 with the pin when the rack-bar will fly back to inoperative position.

It is practically impossible for the pin 27, in moving toward the center of the notch 28, to pass the opening 30 and become engaged against the other shoulder. This is due to the fact that the shoulders 29 are inclined toward the neck opening 30, and the rack-bar will recede, allowing the pin to approach the opening 30 by sliding along the inclined shoulder so that by the time the pin has approximately reached the center of the notch it will have become almost disengaged from the rack-bar.

When it is desired to lock the handles, the rack-bar is simply pushed forwardly by the thumb or finger of the operator and the handles worked up or down until the pin 27 has entered one of the notches 28, whereupon by first releasing the handles and then releasing the thumb from the rack-bar it will be found to have locked itself in position.

What I claim is:—

1. In a valve lifter and compressor, a pair of jaws, handles on said jaws, a fulcrum on one of said handles having openings designed to register with an opening in the other handle, means for pivoting said other handle to the fulcrum in either of two reversed positions at any of the openings in the fulcrum, and means for locking the handles against movement either toward or from each other, said means being spring-urged away from locking engagement and adapted to be held in locking engagement by tension or pressure between the handles.

2. In a valve lifter and compressor, a pair of jaws, handles on said jaws, a fulcrum on one of said handles, means for pivoting said other handle to the fulcrum in either of two reversed positions, and means for locking the handles against movement either toward or from each other, said means being spring-urged away from locking engagement and adapted to be held in locking engagement by tension or pressure between the handles.

3. In a valve lifter and compressor, a pair of tongs having handles and having jaws

adapted to engage a spring for either lifting or compression, a rack-bar pivoted to one of said handles and having detent notches each expanded away from the edge of the bar in both directions longitudinally thereof, a pin secured to the other handle and positioned to be received in any of said notches, and a spring normally urging the

bar away from said pin, engagement of the pin with the rack-bar in the notches being secured by pressure of said pin against either side of any of said notches. 10

Signed at Sioux City, in the county of Woodbury and State of Iowa, this 5th day of February, 1926.

GUSTAV F. STORM.
